UNITED STATES PATENT OFFICE.

LOUIS F. W. MEESE, OF MINNEAPOLIS, MINNESOTA.

ADVERTISEMENT-DISPLAYING MACHINE.

1,230,313.

Specification of Letters Patent.

Patented June 19, 1917.

Application filed January 3, 1916. Serial No. 69,777.

To all whom it may concern:

Be it known that I, LOUIS F. W. MEESE, a citizen of the United States, residing at Minneapolis, in the county of Hennepin and State of Minnesota, have invented certain new and useful Improvements in Advertisement-Displaying Machines; and I do hereby declare the following to be a full, clear, and exact description of the invention, such as will enable others skilled in the art to which it appertains to make and use the same.

My invention has for its object the provision of a simple and efficient means for presenting to view, one after the other, a plurality of display cards or sheets having marked thereon various different printed matter or pictorial illustrations. Generally stated, the invention consists of the novel devices and combinations of devices herein-after described and defined in the claims.

My improved machine is especially adapted and particularly intended for use to present to view, in succession, a multiplicity of different advertisements, but may be used for other analogous purposes, as, for example, a street or station indicator. As a feature of high importance, the invention provides cards or sheets marked with advertisements on both sides; and the machine involves means for presenting the cards or sheets to view, in succession, to display advertisements on one side of the cards, and then for reversing the cards, end for end, and then, in succession, again presenting the same cards to view with their opposite faces exposed. This, of course, doubles the number of advertisements that can be provided with a given number of cards or sheets. The cards, so-called are preferably flexible, or in the form of sheets capable of being bent or rolled.

In the accompanying drawings which illustrate the improved machine, like characters indicate like parts throughout the several views. Referring to the drawings:

Figure 1 is a front elevation of the machine;

Fig. 2 is a front elevation of the machine with the front plate of the case removed;

Fig. 3 is a vertical section taken on the line $x^3 x^3$ of Fig. 2;

Fig. 4 is a section taken approximately on the line $x^4 x^4$ of Fig. 2;

Fig. 5 is a section on the line $x^5 x^5$ of Fig. 4;

Fig. 6 is a fragmentary plan view showing one side of the internal mechanism of the machine; and

Fig. 7 is a section taken approximately on the line $x^7 x^7$ of Fig. 6.

The mechanism of the machine is placed within a rectangular case 1, which, in its front plate, has a large sight opening 2 through which the advertisements, or other matter on the display cards may be exhibited to view, as, for example, shown in Fig. 1.

Mounted in suitable bearings on the sides of the case 1 are upper shafts 3 and 4, and lower shafts 5 and 6. Each of these four shafts carries a pair of laterally spaced sprockets 7 that are located quite close to the side plates of the case 1. A pair of laterally spaced parallel sprocket chains 8 run over the aligned laterally spaced sets of sprockets 7. The upper shaft 4 is located higher than the upper shaft 3, and forwardly inclined channel-shaped tracks 9 extend from points above the shaft 4 to points considerably below the shaft 3. These tracks 9 are located quite close to the inner sides of the adjacent sprockets, and they are rigidly supported by brackets 10 secured thereto, and to the sides of the case 1.

The front lower shaft 5 carries a roller 11, upon which is arranged to run, with very considerable play, a slack take-up cylinder 12, the function of which will hereinafter appear. Light stop fingers 13 are secured on the bottoms of the case and project upward between the lower front portions of the chains 8 and perform functions presently to be noted.

The chains, or endless carriers 8, are each provided with a catch lug 14, a pick-up hook 15 and an escapement tripping or actuating cam lug 16. The said members 14, 15 and 16, on the two chains, are located in transversely opposite pairs, and the said catch lugs and pick-up hooks 15 are projected laterally inward to vertical planes that approximately intersect the outer portions of the inclined tracks 9.

The above noted shafts 3, 5 and 6 are preferably extended completely across the machine, but the rear upper shaft 4 is divided, or cut away between the inclined tracks 9, to afford clearance for the display cards.

The display cards 17 are flexible and may be made either of tough paper or of cloth,

and at their upper and lower edges are provided with, or secured to small rods 18 and 19 that project at their ends and are provided with wheel-like flanges 20 that are 5 adapted to run in the channels of the inclined tracks 9. Normally, the upper rods of the display cards are supported on the said tracks and they are permitted to escape, one at a time, off from the lower end 10 of the said tracks, by a duplex escapement mechanism comprising two escapement levers 21 pivoted to the sides of the case 1, by a small cross shaft 22. These escapement levers 21 are located just inward of the upper front sprockets 7 and they are 15 provided with out-turned fingers 23 adapted to be engaged by the cam lugs 16 of the chains 8. The lower free ends of the escapement levers 21 are formed with reversely acting 20 escapement pallets or teeth 24 and 25, the latter of which are bent inward and upward, to the inner sides of the lower ends of the inclined tracks 9. Normally, the pallets 24 engage the ends of the upper rod of 25 the foremost display card and hold the same and all of the other display cards back upon the inclined tracks, as best shown in Fig. 4.

Operation.

30 Let it first be assumed that the display cards are supported with their rod 18 uppermost and resting on the inclined tracks 9. When the cam lugs 16 come into engagement with the fingers 23 of the escapement levers 21, as shown in Fig. 3, the said levers will be raised, thereby causing the pallet 24 to release the foremost display card, and the pallets 25 in position to hold back the upper rod 18 of the second display card. When 35 the first or foremost display card is thus released, the ends of its upper rod 18 will drop onto the catch lugs 14 of the chains 8, and the ends of the lower rod 19 thereof will drop into position to be engaged by the pick-up hooks 15 of the said chains. Then, as 40 the chains move, the cam lugs 16 will pass the fingers 23 and drop the escapement levers back to normal position shown in Fig. 4, thereby permitting the next display card 45 to move slightly forward with its upper rod against the pallets 24 in position to be released by the next upward movement of the escapement levers. As the chains move forward, the hooks 15, by engagement with 50 the lower rod 19 of the released display card, will be carried downward, and thence upward, until the display card reaches the 55 position shown by dotted lines in Fig. 2, in which position it will be noted the display card has been turned end for end, so that its 60 rod 19, which was previously downward, is now raised, and its rod 18, which was previously at the upper edge, is now at the lower edge and has swung free from the 65 catch lugs 14. At about the position just

stated, the rod 19 which is then upward, will slide off from the pick-up hooks 15 and drop onto the inclined tracks 9, and by gravity, be moved down over the inclined tracks until it is again released by the escapement levers. 70

It will thus be seen that the display cards will be presented to view in succession, first with one face exposed, and then will be inverted, end for end, or edge for edge, and 75 presented in succession with their opposite faces exposed. For example, Fig. 1 shows a card with one face exposed, and Fig. 2 shows the same card with its other face exposed. 80

The endless chains or carrier belt may be driven by any suitable means, either continuously or intermittently. For example, the upper shaft 3 may be projected at one end and provided with a sprocket 3^a, over 85 which a power driven chain might be run.

The escapement levers 21 may be operated by gravity alone, but as shown, they are yieldingly pressed downward by gravity and by the action of light torsion springs 90 22^a anchored to the cross shaft 22 and to one side of the case 1.

The stop fingers 13 prevent the lower rod of a released display card from swinging outward until it has passed below the 95 pick-up hooks 15. The loose cylinder 12 takes up the slack in the flexible card while it is being turned under the shafts 5 and 6.

What I claim is:

1. In a machine of the kind described, 100 the combination with a plurality of cards, of laterally spaced endless belts and driving and guiding means therefor, including front and rear upper belt guiding wheels, inclined tracks for supporting said cards, 105 extending from said rear guide wheels to upper portions of said cards, and pick-up hooks on said belts to receive 110 upper portions of said cards, and pick-up hooks on said belts for engagement with lower portions of the cards, said hooks serving to invert the cards and deliver the same back onto the upper ends of said 115 rails.

2. In a machine of the kind described, 120 the combination with a plurality of cards, of laterally spaced endless belts and driving and guiding means therefor, including front and rear upper belt guiding wheels, 125 inclined tracks for supporting said cards, extending from said rear guide wheels to points below said front guide wheels and terminating in position to discharge said cards onto the downwardly moving sides of said belts, catch lugs on said belts to receive upper portions of said cards, and pick-up hooks on said belts for engagement with lower portions of said cards, 130

said hooks serving to invert the cards and deliver the same back onto the upper ends of said rails, and an escapement device for controlling the discharge of the 5 cards from the lower ends of said rails, said belts having cam lugs for operating said escapement with the properly timed action.

3. In a machine for displaying cards, the combination with inclined rails and a plurality of cards adapted to be supported thereon, of laterally spaced endless belts, upper and lower guiding wheels for said belts arranged to move the same completely around the said rails and to cause the downwardly moved portions of said belts to incline to points backward of the lower ends of said rails, catch lugs on said belts for receiving upper portions of the cards from the lower ends of said rails, and pick-up 10 hooks on said belts for taking up the cards at their lower ends and delivering the same onto the upper ends of said rails.

4. In a machine for displaying cards, the combination with inclined rails and a plurality

of cards adapted to be supported 25 thereon, of laterally spaced endless belts, upper and lower guide wheels for said belts arranged to move the same completely around the said rails and to cause the downwardly moved portions of said belts to incline to points backward of the lower ends of said rails, catch lugs on said belts for receiving upper portions of the cards from the lower ends of said rails, and pick-up 30 hooks on said belts for taking up the cards at their lower ends and delivering the same onto the upper ends of said rails, escapement levers controlling the discharge of the cards from the lower ends of said rails, and cam lugs on said belts for operating said escapement levers with properly timed actions. 35

In testimony whereof I affix my signature in presence of two witnesses.

LOUIS F. W. MEESE.
